2,681,957

AIR VELOCITY RESPONSIVE SNAP ACTION SWITCH

Paul L. Schneider, Anderson, Ind., assignor to
General Motors Corporation, Detroit, Mich., a
corporation of Delaware

Application January 13, 1950, Serial No. 138,317

3 Claims. (Cl. 200—81.9)

1

This invention relates to a system of controls for a plurality of sounding signals for use on automotive vehicles.

It is an object of the present invention to provide a system of control for a pair of horns or sounding signals which is normally conditioned so that only one of the signals can be sounded when the vehicle is traveling below a certain speed suitable for city driving or when at rest. When the automobile speed attains a certain value higher than permissible for city driving all signals will be sounded whenever the horn button is pressed to close a circuit.

In the disclosed embodiment of the invention, the object is obtained by use of an automatic switch which is responsive to the motion of the vehicle moving at a certain speed above that permissible for city driving or when the engine is accelerated when vehicle is at rest. When the vehicle is traveling at a speed over 35 miles an hour this automatic switch will close to condition a relay which becomes effective to connect a source of current with all horns when the push button switch is pressed to its closed position. When the vehicle is stationary and not accelerated or when the vehicle is moving below 35 miles per hour the automatic switch is opened and the relay will not be in condition to connect the current source with all of the horns, although the push button may be closed to connect one of the horns with the source.

Further objects and advantages of the present invention will be apparent from the following description, reference being had to the accompanying drawings wherein a preferred embodiment of the present invention is clearly shown.

In the drawing:

The single figure of the drawing is a wiring diagram of the invention.

A generator 10 driven by the engine is connected by a wire 11, a cut-out relay 12 and a wire 13 with a battery 14 grounded at 15. A horn or warning signal 16 of low volume for city driving and a horn or warning signal 17 for country driving is connected with the battery or current source. The horn 16 is connected with the battery 14 by a wire 18 connected with a leaf spring 19 of horn relay 20. The leaf spring 19 carries a contact 21 normally separated from stationary contact 22. The leaf spring 19 is attracted by an electromagnet including a core 23 and a coil 24 having one end connected to a terminal 25 which supports one end of the leaf spring 19. The circuit of the coil 24 is controlled by a control switch or horn button 26 comprising stationary contact 27 connected with the coil 24 and a contact 28 which is grounded. A movable contact 29 of the switch is held away from the contacts 27, 28 by a spring 30. When the movable contact 29 is moved into engagement with contacts 27, 28

2

the relay coil 24 is energized to attract leaf spring 19 to close relay contacts 21, 22 in order that the low volume horn may be connected with the battery through a wire 31 connected with contact 22 and a wire 32 connected to a terminal of the horn 16. The other terminal of horn 16 is grounded.

Wire 32 is connected also with a terminal 33 of relay 34 having a core 35 surrounded by a coil 36, one end of coil 36 is connected with terminal 33. A spring blade 37 fixed to the terminal 33 carries a contact 38 engageable with a contact 39 and connected with a terminal of a country horn 17. The other terminal of horn 17 is grounded.

The other end of the coil 36 of relay 34 is connected by a lead 36a with a terminal 41 of a switch unit 40. The switch unit 40 includes a sheet metal base 42 having a flange 43 against which the periphery of a diaphragm 44 is clamped by a flange 45 of a cover 46. A pipe or conduit 47 connects the cover 46 with a funnel or scoop 48 which receives a blast of air directed from the engine cooling fan 49 mounted on a shaft 50 and driven by the engine.

The base 42 has a central bushing 51 for guiding a rod 52 having an enlarged portion to provide a shoulder 53 against which a washer 54, a plate 55, the diaphragm 44, and a washer 56 are urged by riveting over at 57 the upper end of rod 52. A plate 59 attached to the base 42 provides a bracket 60 for supporting a pin 61 upon which a lever 62 is pivoted. The lever 62 has an extension 63 to which one end of a spring 64 is connected. The other end of the spring 64 is connected to an extension 65 of the plate 59. The spring 64 urges the lever 62 counterclockwise into engagement with rod 52 and rod 52 is urged upwardly as viewed in the drawing, said motion being stopped by virtue of engagement of diaphragm 44 with the cover 46 at the surface 46s.

The pin 61 also provides a pivotal support for a lever 66 carrying a contact 67 normally separated from a contact 68 supported by a bracket 69 electrically connected with a bracket 70 into which the terminal screw 41 is threaded. Brackets 69 and 70 are supported by the base 42 but are insulated therefrom. A U-shaped spring 71 is connected with levers 62 and 66 and normally biases lever 66 clockwise so that it normally engages a nonconducting stop 72 supported by bracket 70. Therefore, the contact 67 is normally separated from contact 68.

The edges of plate 59, attached to base 42, are surrounded by the edges of the sides of cover 73 which is retained by the screw 41 which is insulated from the cover 73 by insulation 74. The cover 73 is not hermetically sealed against the base 42. A vent 42a in base 42 is relatively small so as to retard air flow as the diaphragm moves

thereby minimizing the surging action of the switch.

For normal city driving, the circuit is in the condition shown in the drawing. Assuming that the legal city speed limit is around 35 miles an hour, the pressure above the diaphragm 44 obtained by the rotation of the engine cooling fan 49 is not sufficient to overcome the spring 64. Therefore, when the push button 26 is moved to cause contact 29 to bridge contacts 27 and 28 the current source will be connected with the low volume horn 16 to give a signal enduring so long as the button is depressed but the horn 17 of high volume will not be connected with the source. When driving at 40 miles per hour or greater, or when the engine is accelerated to cause the fan to rotate at a speed such as to cause the pressure above the diaphragm 44 to be sufficient to overcome spring 64 the rod 52 moves down causing the lever 62 to move clockwise. When the center line of action of the ends of the U-spring 71 passes from below to above the pivot 61 the lever is biased counter-clockwise to cause its contact 67 to engage contact 68. When that happens the relay coil 36 of relay 34 will become energized when the push button switch 26 is closed through the following circuit: wire 13, wire 18, leaf spring 19, contacts 21, 22 of relay 20, wires 31, 32, terminal 33, coil 36, lead 36a, terminal 41, bracket 70, bracket 69, contacts 68, 67, lever 66 and switch base 42 which is grounded. When the coil 36 has been energized, the core 35 will attract leaf spring 37 to move contact 38 into engagement with contact 39 and the horn 17 will receive current from the source as will horn 16. When the speed of the engine falls to 35 miles an hour or lower such that the air pressure in duct 48 is insufficient to maintain the proper circulation through the duct, the switch in unit 34 will open thereby rendering relay magnet coil 36 ineffective to attract leaf spring 37 to close contacts 38, 39 when the push button 26 switch is closed.

Although the invention has been described as having the pipe or conduit 47 leading from the diaphragm chamber of the switch unit 40 and projecting into the funnel or scoop 48 which receives the air blast from the engine cooling fan, it will be understood that the scoop 48 could be eliminated. It is obvious that certain changes in shape, size and arrangement of parts may be made so that the conduit 47 would be in any air stream which produces sufficient pressure to operate the diaphragm of the switch unit 40.

While the embodiment of the present invention as herein disclosed, constitutes a preferred form, it is to be understood that other forms might be adopted.

What is claimed is as follows:

1. An air velocity responsive snap action switch, comprising in combination, a stationary contact; a movable arm supporting a contact, a second movable arm, each arm having one end pivotally mounted on a common axis; a snap spring interconnecting the free ends of the arms; a coiled spring having one end connected to a stationary part and having its other end connected to the second lever to move it in one direction so that the center line of action of the ends of the snap spring is below the axis of the levers to hold normally the contacts separated; an air collecting duct; a compact tube positioned within the duct; a chamber connected with said tube and partitioned into two compartments by an air impervious

diaphragm; an operating rod carried by the diaphragm and engaging the second arm, said rod acting upon said second arm, when the velocity of air in said tube reaches a predetermined value, to move same against the action of the coiled spring to move the center line of action of the ends of the snap spring above the axes of the arms whereupon the first arm is biased to cause the contact to engage the stationary contact.

2. An air velocity responsive snap action switch, comprising in combination; a stationary contact; a movable arm supporting a contact, a second movable arm, each arm having one end pivotally mounted on a common axis; a snap spring interconnecting the free ends of the arms; a coiled spring having one end connected to a stationary part and having its other end connected to the second lever to move it in one direction so that the center line of action of the ends of the snap spring is below the axis of the levers to hold normally the contacts separated; an air collecting duct; a compact tube positioned within the duct; a diaphragm movable in one direction in response to pressure increase in the tube; a plunger actuated by the diaphragm and engageable with the second arm to move it in a direction against the force of the coiled spring to move the center line of action of the ends of the snap spring above the axes of the arms whereupon the first arm is moved with a snap action to cause its contact to engage the stationary contact, said coiled spring being operable, when the pressure in the tube is reduced to a certain value, to cause the arms to move about their axes and cause the ends of the snap spring to assume the first mentioned center line of action.

3. An air actuated switch comprising in combination; a stationary contact; a first lever carrying a contact adapted to engage the stationary contact; a second lever having an angular leg, said levers being pivotally mounted on a common axis, said levers having opposed abutments adjacent their free ends; a U-shaped snap spring having opposite ends operatively connected with the abutments and adapted to shift the center line of action of the ends of the snap spring on either side of the axes of the levers; resilient means having one end connected to the leg of the second lever, said resilient means being operable to urge the second lever in one direction so that center line of action of the ends of the leaf spring is on one side of the axes of the levers to separate the contacts; an air conducting duct, a chamber adjacent the duct; an air impact tube connected with the duct and the chamber; a diaphragm movable in one direction in response to pressure in said tube; an operating rod carried by the diaphragm and engaging the second lever and operable to move said second lever in response to movement of the diaphragm in said one direction to cause the center line of the ends of the snap spring to shift to the other side of the axes of the levers to close the contacts.
